(57) **CLAIM**

The ornamental design for a training aid, as shown and described.

DESCRIPTION

FIG. 1 is a front perspective view of a training aid showing our new design;

FIG. 2 is a front elevational view thereof, the rear elevational view is identical to the front elevational view;

FIG. 3 is a right side elevational view thereof, the left side elevational view is identical to the right side elevational view;

FIG. 4 is a top plan view thereof;

FIG. 5 is a bottom plan view thereof;

FIG. 6 is a cross-sectional view taken along the line A-A in FIG. 4;

FIG. 7 is a side view of the training aid in use; and,

FIG. 8 is a side view of the training aid in an alternate position.

The broken lines depict unclaimed environmental subject matter.

1 Claim, 5 Drawing Sheets
